**METHOD OF FORMING CYLINDER LOCK
HOUSING OF STRIP MATERIAL**Fred J. Russell, 3800 Don Felipe Drive,
Los Angeles, Calif.

Filed June 23, 1958, Ser. No. 743,686

5 Claims. (Cl. 29—463)

The invention relates to lock housings and particularly lock housings for a type of lock commonly designated a cylinder type lock. More particularly the patent has reference to a method of forming such a cylinder lock housing of strip material instead of forming it by machining the device from cast or extruded stock.

One of the elements of door lock hardware which has for a long time presented certain problems to the designer and manufacturer has been the lock housing for cylinder type locks in which there is customarily provided a series of spaced cylindrical bores designed to receive pin tumblers and their springs and to retain them in proper actuating position. Although reliable and effective cylinder lock housings have been in substantially widespread use, they have been somewhat costly to manufacture because of the established practice of machining them from solid brass stock. The machining operation is not only costly from the point of view of raw material, but is wasteful in that a substantial amount of scrap must necessarily result and further because an unnecessarily large number of manufacturing operations have been needed. Further still, because of the peculiar design of these parts and the necessity for accurately aligning the pin tumbler bore, the manner of forming those bores has been such that some apertures necessarily made in the manufacturing process have necessitated the making of additional apertures not useful in the finished product and which necessitate a still additional operation to seal them or plug them and refinish the surface before the device is acceptable as an operating structure.

It is therefore among the objects of the invention to provide a new and improved cylinder lock housing and method of forming the same which makes possible the fabrication of the parts from strip material as a consequence of a relatively few, simple manufacturing operations.

Another object of the invention is to provide a new and improved method of forming cylinder lock housings which makes use of a certain few stamping and folding operations, thereby constituting a very simple manufacturing process which, however, results in a rugged and dependable type of device.

Still another object of the invention is to provide a new and improved method for the forming of a cylinder lock housing which entirely eliminates machining operations and substitutes therefor die operations on relatively flat stock accompanied by a subsequent simple folding operation in certain forms of the invention.

Still further among the objects of the invention is to provide a new and improved method of forming cylinder lock housings by means of which complementary halves of a cylinder lock housing can be formed by a stamping or pressing operation and the halves thereafter positioned face to face and connected together by bending portions of the material, thereby making possible the fabrication of a dependable lock casing by simple and inexpensive means.

A still further object of the invention is to provide a new and improved cylinder lock housing of thin gage sheet material with portions molded for reception of operating parts and exterior elements thereon interlocked to provide a rugged durable device.

With these and other objects in view, the invention consists in the method for achieving the construction, arrangement and combination of the various parts of the device whereby the objects contemplated are attained as hereinafter set forth, pointed out in the appended claims and illustrated in the accompanying drawings.

In the drawings:

Figure 1 is a perspective view of a piece of metal strip from which the device is formed.

15 Figure 2 is a perspective view showing the piece after completion of the first phase of its forming.

Figure 3 is an end elevational view showing the second phase of its forming.

10 Figure 4 is an end elevational view of the device after final forming.

20 Figure 5 is a cross-sectional view taken on the line 5—5 of Figure 4.

Figure 6 is a perspective view of a two-piece device after completion of the first phase of its forming.

25 Figure 7 is an end elevational view of the two-piece device after the final forming.

In the exercise of one form of the method productive of the device illustrated in Figures 1 through 5 there is provided a piece of strip material of substantially uniform thickness which, if preferred, may be cut from a length of strip material of appropriate size and thickness. The simple piece of strip material is indicated by the reference character 10. It will be noted that by reason of making use of a strip of the material of adequate size, the pieces 10 may be stamped out, leaving desired tabs of metal at appropriate locations during a cutting process. It should be understood that the cutting may, if desired, be included as part of the novel stamping process.

30 40 45 An acceptable means of employing the method is to have prepared a pair of respective male and female dies, the female die having the shape and configuration of an underside 11 of a part resulting from the first phase of the method and the male die having a form conforming to an upper face 12 of the part.

It should further be appreciated that the female die (not shown) can be simple in that it may comprise recesses adapted to receive and form the under face of the piece as the male die (not shown) having complementary projections is forced into position to form the upper face 12.

50 55 60 By press operations all of the configurations on both upper and lower sides of the piece may be formed simultaneously. The depressions made mention of comprise a wide deep recess indicated generally by the reference character 13 and which may be said to comprise complementary impressions 14 and 15 on respectively opposite sides of a longitudinal center line 16. Generally speaking the recess 13 will be relatively flat along the longitudinal center line at this step in the process but will have a sufficient transverse length so that it will form a cylindrical hole of proper size following the ultimate step of the method.

65 70 75 The portions of the strip which become the parts forming the impressions 14 and 15 may appropriately be defined as inner sections of the strip or, in other words, sections closest to the longitudinal center or dividing line.

Similarly adjacent the portion forming the impression 15 is a part of the initially selected piece which may appropriately be defined as an outer section 17 while

on the other side is another piece which may be appropriately defined as an outer section 18.

These outer sections in each instance have impressed into their inner faces a series of spaced semi-cylindrical depressions. Those depressions made in the outer section 17 are identified with the reference character 19. Those depressions made in the outer section 18 have been given the reference character 20. It is preferable that these depressions be substantially semi-cylindrical in form and that the depressions 19 match and be complementary to the depressions 20. Strips 21 act as spacers between adjacent depressions. At the outer ends of the depressions 19 are end walls 19' and end walls 20' close to the outer ends of the depressions 20.

In order to fasten the formed piece in assembled condition, end tabs 22 and 23 may be formed on end faces 24 and 25, respectively. Similarly tabs 26 and 27 may be formed respectively on end faces 28 and 29. Adjacent the end walls 19' on the outer section 17 is a flat strip 39 from which extend tabs 31 and 32. Similarly on the outer section 18 is a flat strip 33 from which extend tabs 34 and 35 staggered with respect to the tabs 31 and 32.

After the strip has been given the form illustrated in Figure 2 which may be accomplished by a punch press machine where appropriate female and male dies are made use of, the initially formed part is ready to be folded into final shape. This may be accomplished effectively by employment of a mandrel 36 which has the proper diameter in order to result in the formation of a hole of proper dimension for reception of a conventional cylinder plug used in the type of cylinder lock here made reference to.

The mandrel 36 is placed in the recess 13 where it may be forcibly held by appropriate conventional means not important to the steps herein particularly described. With the mandrel in place the outer sections 17 and 18 are pulled over the exposed face of the mandrel toward each other until the strips 21 are pressed face to face, as illustrated in Figure 3. This step in the method includes carefully aligning the semi-cylindrical depressions with each other so that when the outer sections are pressed together, the complementary depressions will complete the formation of a series of spaced parallel pin tumbler bores. By use of appropriate and well-known folding apparatus, the opposite sections 17 and 18 may be held in proper position, at which time the impressions 14 and 15 are likewise turned properly over the cylindrical circumference of the mandrel 36. While being firmly held in the last described position, the tabs 22, 23, 26 and 27 may be bent around the sides as shown in Figure 4 and there forced into engagement by pressure in order to firmly anchor the parts in assembled condition.

During the same phase of the process, tabs 31 and 32 are folded between tabs 34 and 35 and around the outer face of the flat strip 33. Similarly the tabs 34 and 35 are folded between the tabs 31 and 32 and pressed against the outer face of the flat strip 30.

Where the first method step is effectively performed and the impressions made with a sufficient degree of fidelity, the pin tumbler bores will not need further sizing or machining and the employment of the mandrel 36 will assure that the finally formed cylindrical recess 13' will be true and correct and properly receptive of the cylinder lock when that part is ultimately assembled with it.

The method heretofore described contemplates forming the entire cylinder lock housing from a single piece of strip material. Some advantages, however, may be derived from employing two separate pieces of material about half the breadth of the piece 10. When this modified form of the method is practiced, there will be struck complementary half sections 40 and 41, illustrated in Figure 6. The half sections may be made complementary in all respects to the extent that there is formed

in the half section 40 a semi-cylindrical recess 42 and in the half section 41 a semi-cylindrical recess 43.

At the same time as the semi-cylindrical recesses 42 and 43 are formed, there are also formed in the half section 40 a series of spaced parallel semi-cylindrical depressions 44 having end walls 45. Similarly in the half section 41 there will be formed a corresponding set of complementary spaced semi-cylindrical depressions 46 having end walls 47. Also during the forming of the half section 40, tabs 48 and 49 may be formed on opposite ends 50 and 51 respectively. Tabs 52 and 53 are formed in substantially the same fashion on ends 54 and 55 of the half section 41, the tabs at opposite ends being staggered with respect to each other. A flat strip 60 having tabs 61 and 62 is formed on the half section 40 and a flat strip 63 having tabs 64 and 65 is formed on the half section 41. Tabs on opposite sides in this instance also are staggered with respect to each other.

To interlock the half sections together at the area of the recess 42 and 43 there are provided apertures 66 and 67 in the half section 40 in alignment with tabs 68 and 69 in the half section 41. Tabs 70 and 71 in half section 40 are formed in alignment with apertures 72 and 73 in the half section 41. As shown, the staggered relationship is maintained to permit the necessary interlocking of the projecting parts.

It will be appreciated that following conventional practice multiple dies may be constructed so that a large number of half sections 40 and 41 may be struck simultaneously at one single cycle of the machine.

To form the finished part illustrated in Figure 7, the half sections 40 and 41 are matched and placed in position face to face after the tabs 68, 69, 70 and 71 are inserted through their respective apertures 66, 67, 72 and 73. The half sections are then pressed together so that strips 74 of the half section 40 are pressed face to face into engagement with strips 75 of the half section 41. While held firmly in place the tabs 48, 49, 52 and 53 are bent around the opposite sides, as shown in Figure 7. Tabs 61 and 62 are bent around the outer face of the flat strip 63 and tabs 64 and 65 are bent around the outer face of the flat strip 60. Tabs 61 and 62 may be bent against the opposite half section and tabs 64 and 65 may be bent outwardly, as shown in Figure 7, to assure a firm interlock. Tabs 68, 69, 70 and 71 may be bent as shown in Figure 7, care being exercised to preserve the contours of surfaces 42 and 43. In this form employment of a mandrel like the mandrel 36 may be dispensed with.

It will be understood and appreciated from the foregoing described method with respect to both forms thereof that the operations of forming cylinder lock housings heretofore in vogue have been very greatly simplified by the method defined and disclosed. Moreover, by use of the method in the manner described it is possible to make use of stock material of a much less expensive type in order to ultimately form the cylinder lock housing. By use of the method and technique of the disclosed invention, moreover, a substantial degree of precision is assured with respect to forming both the recess for the lock cylinder and the bores for the pin tumblers. The employment of the method therefore results in production of parts for locks which are materially less costly, resulting in an appropriate benefit to all types of users.

While I have herein shown and described my invention in what I have conceived to be the most practical and preferred embodiment, it is recognized that departures may be made therefrom with the scope of my invention, which is not to be limited to the details disclosed herein but is to be accorded the full scope of the claims so as to embrace any and all equivalent methods.

Having described my invention, what I claim as new and desire to secure by Letters Patent is:

1. A method of forming a cylinder lock housing hav-

ing a cylinder plug recess and pin tumbler bores in communication therewith comprising dividing a strip of metal stock on opposite sides of a longitudinal dividing line into an inner section on each side adjoining the center line and an outer section on each side adjoining the respective inner section, impressing into one face of one of said sections on each side of the dividing line complementary impressions of opposite sides of said cylinder plug recess, impressing into corresponding faces of the other of said sections on each side of the dividing line a plurality of parallel inwardly open and outwardly closed pin tubular depressions, spacing said depressions laterally with respect to each other, making the depressions on opposite sides complementary to each other and extending transversely of the axes of said first identified impressions, folding said opposite sides along the dividing line thereby to form the cylinder plug recess and the outwardly closed pin tubular bores and fastening said opposite sides together.

2. A method of forming a cylinder lock housing having a cylinder plug recess and pin tumbler bores in communication therewith comprising dividing a strip of metal stock on opposite sides of a longitudinal dividing line into an inner section on each side adjoining the dividing line and an outer section on each side adjoining the respective inner section, impressing on one face of said inner sections complementary impressions of opposite sides of said cylinder plug recess, impressing into corresponding faces of said outer sections a plurality of parallel spaced depressions of said pin tumbler bores with open inner ends communicating with the impressions extending transversely to the axes of said recesses and making closed outer ends for said depressions, making the depressions on opposite sides complementary to each other, folding said inner sections along the dividing line thereby to form the cylinder plug recess, and fastening said opposite sections in face to face engagement with opposite depressions of said pin tumbler bores facing each other whereby to complete the formation of said pin tumbler bores in outwardly closed and inwardly open form.

3. A method of forming a cylinder lock housing having a cylinder plug recess and pin tumbler bores in communication therewith by use of dies and a cylindrical mandrel comprising dividing a strip of metal stock of substantially uniform thickness on opposite sides of a longitudinal dividing line into an inner section on each side adjoining the dividing line and an outer section on each side adjoining the respective inner sections, impressing on one face of said inner sections complementary impressions of opposite sides of said cylinder plug recess, impressing into corresponding faces of said outer sections a plurality of parallel spaced semi-cylindrical depressions of said pin tumbler bores with open inner ends in communication with said respective impressions and with closed outer ends extending transversely to the axes of said depressions, making the semi-cylindrical depressions on opposite sides with closed outer ends complementary to each other and with edges of sides and outer ends of the depressions in the same plane, providing flat areas outwardly of said closed outer ends on a plane with the edges thereof and providing fasteners on said areas, folding said inner sections along the dividing line over said cylindrical mandrel thereby to form the cylinder plug recess, and securing the edges of said depressions against movement with respect to each other by fastening said outer sections at end edges at locations

removed outwardly from said closed outer ends and at side edges thereof in face to face engagement with opposite semi-cylindrical depressions of said pin tumbler bores facing each other whereby to complete the formation of said pin tumbler bores in outwardly closed and inwardly open form.

4. A method of forming a cylinder lock housing having a cylinder plug recess and pin tumbler bores comprising preparing two pieces of metal of substantially uniform size and thickness, dividing each piece into a first section and a second section, impressing into corresponding faces of said first sections complementary recesses corresponding to partial portions of said cylinder plug recess, impressing into corresponding faces of said second sections transversely extending spaced parallel depressions in precisely located positions relative to the recesses in the respective first section, making said depressions in the opp site second sections respectively complementary to each other, providing tabs at outer ends respectively of said first sections and said second sections, and providing in opposite sections receiving means for said tabs in positions wherein the tabs when received therein will be secure against shifting laterally, placing said faces of the two pieces in face to face engagement and folding said tabs into anchoring relationship with said pieces whereby said pieces are fastened together with recesses forming the plug recess and the complementary depressions form pin tumbler bores in precisely located relationship with said plug recess.
5. A method of forming a cylinder lock housing having a cylinder plug recess and pin tumbler bores comprising preparing two pieces of metal of substantially uniform size and thickness, dividing each piece into an inner section and an outer section, impressing into corresponding faces of said inner sections semi-cylindrical complementary recesses corresponding to half portions of said cylinder plug recess, impressing into corresponding faces of said outer sections transversely extending spaced parallel semi-cylindrical depressions, said depressions in the opposite outer sections being made respectively complementary to each other, forming tabs at edges of one of said pieces and forming at corresponding edges of the other of said pieces opening in alignment with selected tabs, placing said faces of the two pieces in face to face engagement and placing said tabs in the corresponding openings whereby to align the recess and the depressions and said pieces at outer and end edges respectively of the outer sections and at outer edges of the inner sections thereof whereby the bending said tabs of one piece over the edge of the opposite piece whereby to anchor semi-cylindrical complementary recesses form the plug recess and the semi-cylindrical depressions form the pin tumbler bores communicating with said plug recess.
